ATTORNEY

UNITED STATES PATENT OFFICE.

PHILIP BURNS, OF NORWICH, CONNECTICUT.

DESIGN FOR A LINK FOR BICYCLE-CHAINS.

SPECIFICATION forming part of Design No. 27,957, dated December 7, 1897.

Application filed May 27, 1897. Serial No. 638,473. Term of patent 3½ years.

To all whom it may concern:

Be it known that I, PHILIP BURNS, a citizen of the United States, residing at Norwich, in the county of New London and State of Connecticut, have invented and produced a new and original Design for a Link for Bicycle-Chains, of which the following is a specification, reference being had to the accompanying drawing, forming a part thereof, which drawing is a side face view of a link, showing my new design.

The leading or material feature of my said design consists in the peculiar form of the outline of the link, in connection with a peculiar form and arrangement of certain openings within the field inclosed by the outline of the link. Said outline, as here shown, instead of being curved inward between the ends and extending diagonally from said curves, as in my design patented August 11, 1896, No. 25,914, consists of parallel sides *a a*,

connected by semicircular ends *b b*. Within the field inclosed by said outline is a circular opening *c*, that is concentric with one of the semicircular ends *b*, and between said circular opening and the other end of the link is an opening *d* of elongated slot form, whose ends are semicircular and of the same diameter and whose side lines are broken or indented, as at *e e*, instead of being narrower at one end than at the other end and without such indentations, as in my previously-patented design above referred to.

Having described my invention, what I claim as new, and desire to secure by Letters Patent, is—

The design for a link for bicycle-chains as herein shown and described.

PHILIP BURNS.
